PULL TAB FOR A REMOVABLE TEAR PORTION

Don B. Peters and George T. Powell, Dayton, Ohio, assignors, by mesne assignments, to Ermal C. Fraze, Dayton, Ohio

Filed Feb. 12, 1968, Ser. No. 10,525

Term of patent 14 years

(Cl. D9—256)

FIG. 1 is a perspective view of a pull tab for a removable tear portion embodying our new design;

FIG. 2 is a top plan view thereof;

FIG. 3 is a side elevational view thereof;

FIG. 4 is an end elevational view taken from the left end of FIG. 2.

We claim:

The ornamental design for a pull tab for a removable tear portion, substantially as shown.
